LANTERN AND REFLECTOR SUPPORT WITH
UNIVERSALLY ADJUSTABLE BASE

Ernest O. Brow, Anderson, Ind.

Application July 18, 1949, Serial No. 105,425

3 Claims. (Cl. 240—52)

1

This invention relates to certain new and useful improvements in a lantern hood or guard and reflector.

The primary object of the invention is to provide a lantern hood or guard and reflector designed for many uses, one of which uses is herein illustrated as being in connection with a ship or boat with the hood or guard mounted on the gunwale of the boat.

A further object of the invention is to provide a lantern hood or guard of the foregoing character constructed for free rotary adjustment whereby light rays from the lamp may be directed in the desired direction, with the mounting elements for the hood or guard providing for angular adjustments in vertical directions.

A still further object of the invention is to provide a bracket mounting for the lantern hood or guard whereby the clamping elements of a bracket may be either vertically or horizontally positioned for engagement with an appropriate support.

It is a still further object of the invention to provide a lantern hood or guard in which the wall thereof that is of substantially cylindrical construction is formed of overlapping sections that may be vertically adjusted to accommodate lamps of different heights.

With the above and other objects in view that will become apparent as the nature of the invention is better understood, the same consists in the novel form, combination and arrangement of parts hereinafter more fully described, shown in the accompanying drawings, and claimed.

In the drawings:

Figure 1 is a front elevational view of the lantern hood or guard mounted on the gunwale of a boat with a lantern supported in the guard.

Figure 2 is a side elevational view with the gunwale shown in section and a part of the clamping mechanism of the mounting bracket illustrated by dotted lines in a released position.

Figure 3 is a horizontal sectional view taken on line 3—3 of Figure 2.

Figure 4 is a horizontal sectional view taken on line 4—4 of Figure 2 illustrating a four-spider leg frame for the rotatable support of the lantern guard.

Figure 5 is a detailed sectional view taken on line 5—5 of Figure 1, showing the manner of attaching one end of the lifting handle to the upper end of the lantern and upper end of the guard or hood.

Figure 6 is an enlarged detail sectional view 55

2

taken on line 6—6 of Figure 1, showing the mounting bracket and clamp for the lantern hood or guard and the rotatable base support for the lantern.

Figure 7 is a plan view of a modified form of mounting base for the hood or guard and shows three spider legs as contrasted with the showing in Figure 4.

Figure 8 is a plan view of a modified form of the base plate for the mounting of the lantern and shows a series of radial slots having adjustable clamps therein for the lantern base.

Figure 9 is a detailed sectional view taken on line 9—9 of Figure 8.

Figure 10 is an elevational view of a modified form of lantern hood or guard wherein the same is formed of two overlapping vertically adjustable sections to accommodate lanterns of different heights.

Figure 11 is a detailed sectional view taken on line 11—11 of Figure 10, and

Figure 12 is a fragmentary plan view of the perforated head portion of the hood or guard.

Referring more in detail to the accompanying drawings, there is illustrated a lantern hood or guard and reflector that comprises a supporting frame designated in general by the reference character 15, a lantern hood or guard mounted thereon and generally indicated at 16, while the lantern mounted within the hood or guard is shown at 17.

The supporting frame, as shown most clearly in Figures 2, 4, and 6, comprises a ring 18 having a 180° section 19 thereof set in a plane below the plane of the other section 20 for purposes presently to appear. Crossed reinforcing spider arms 21 and 22 are connected at their outer ends to the ring and their crossing points form a hub 23. The spider arm 22 adjacent the

ring section 20 carries an upwardly and angularly directed arm 24 for the pivotal mounting of a vise-like clamp that has a bar 25 carrying depending end lugs 26 and 27 adapted to straddle a support 28 such as a gunwale or the like with the leg 26 engaged with one side of the gunwale. A clamping screw 29 threaded through the other leg 27 engages the other side of the gunwale for the rigid mounting of the supporting frame. An arm 30 extends from the end of the bar 25 for pivotal mounting as at 31 to the upper end of the arm 24 as shown in Figures 2 and 6.

The lantern hood or guard includes a base plate 32 of disk form and a headed bolt 33 passes centrally downwardly through the base plate 32 and the hub 23 of the spider arms for the re-

ception of lock nuts 34 on the lower end thereof, washers or gaskets 35 being interposed between the base plate 32 and hub 23 whereby the disk plate is freely rotatably mounted on the supporting frame. A plate upon which the lantern 17 is fixedly mounted is indicated by the reference character 36 and is supported on the base plate 32, the bolt 33 passing centrally therethrough, while said plate 36 is anchored at suitably spaced points by screws or the like 37 passing therethrough and entering the base plate 32 as shown in Figure 6.

A split clamping ring 38 surrounds the plate 36 and extends thereabove as illustrated for engagement with a base flange on the lantern 17 and said split ring is then secured together at its split ends by lug and bolt combinations 39 as shown in Figures 1 and 3.

The hood or guard 16 for the lantern is secured to the base plate 32 and includes a vertically semi-cylindrical wall 40 surrounding the base plate at its lower end and anchored thereto as at 41. An arched hood 42 is secured to the upper end of the wall 40 and has a lip extension 43 at its upper end that overlies the upper end of the cap 44 of the lantern 17 as shown in Figure 5. A lifting handle 45 for the guard or hood has one end leg 46 thereof anchored to the hood 42 in proximity of the lower rear edge thereof, while the other end leg 47 of the handle extends over the lip 43 on the hood 42 with a threaded bolt 48 passed upwardly through the lantern cap 44, lip 43, handle leg 47 for the reception of a retaining nut 49. The reference character 50 designates a hinged bail secured to the lantern as shown in Figures 1 and 2. Access may be had to the lantern 17 through the rear side of the wall 40 of the lantern hood or guard by the provision of an opening 51 in the lower end of the wall 40 that is normally closed by a cover 52 hinged to the wall as at 53.

When it is desired to rotatably adjust the hood 16 that is fixed to the base plate 32, the latter may be readily grasped at its forward side which is made possible by the lowering of the section 19 of the ring of the supporting frame. It will also be observed that the upper section 20 of the ring 18 has an upset portion 20a to provide a clearance for movement of the bar 25 of the bracket clamp. Also, the bar 25 of the bracket clamp carries a transversely extending arm 54 at its underside for flat engagement with the upper side of the support 28 to provide a stable mounting for the bracket clamping mechanism. It will be understood that the inner face of the wall 40 of the hood or guard and the arched hood 42 have polished surfaces for light reflection. The hood 42 may be perforated as at 55 as shown in Figure 12 for the escape of heat rising from the lantern.

In lieu of the ring 18 and its four spider arms 21 and 22, a skeleton frame may be substituted as shown in Figure 7 wherein the central hub 23a has two arms 21a and one arm 22a radiating therefrom, the arm 22a carrying at its outer end a block enlargement 56 on which the clamp arm 30 may be pivotally mounted.

The split clamping ring 38, as shown in Figure 6, for anchoring the lantern 17 in position may be eliminated and the plate 36a shown in Figure 8 may have radial slots 57 therein for the slidable mounting of adjustable clamps 58 that engage the base of the lantern as will be

understood from an inspection of said Figure 8 and also Figure 9.

The lantern hood or guard 16 is shown in Figures 1, 2, and 6 as comprising a single semi-cylindrical wall 40, but in Figures 10 and 11 a modification of the hood or guard is shown and it comprises upper and lower semi-cylindrical wall sections 40a and 40b that are assembled in vertically telescoping relation with interfitting beaded edges 59 shown in Figure 11 that are held in adjusted position by the set screws 60 associated with said beaded edges. An extensible structure of this character will accommodate a lantern of different heights.

From the above detailed description of the invention, it is believed that the construction and operation thereof will at once be apparent, it being noted that the supporting frame 15 forming the base structure of the hood or guard may be mounted on the gunwale of a boat as illustrated in Figures 2 and 6, or the supporting frame may be mounted on a flat table support or the like upon laterally shifting the U-shaped vise-like clamp comprising the bar 25 and lugs 26 and 27. Rotary adjustment of the hood or guard is facilitated by its axial rotation on the vertical pin 33 so that light rays may be cast in the desired direction.

While there are herein shown and described the preferred embodiments of the invention, it is nevertheless to be understood that minor changes may be made therein, such as will fall within the scope of the invention as claimed.

I claim:

- 35 1. In light-ray directing assemblages, wherein a lantern forms the lighting unit and a reflector cooperates therewith in providing light-ray direction of emission, and wherein the assemblage as such is removably positionable relative to a supporting unit, an assemblage of such type comprising a base unit of skeleton type having clamping means for adjustably engaging the supporting unit, said base unit including a perforated hub with the perforation axis extending vertically, the clamping means of the base unit being operative to fixedly position the base unit on the supporting unit, a lantern-supporting plate symmetrical to such vertical axis and mounted on the base unit for pivotal adjustment relative to the base unit and with such vertical axis as the axis of pivotal movement, lantern gripping means mounted upon and symmetric relative to and movable with said plate on such vertical axis, bolt means extending on such vertical axis for anchoring the plate to the base unit in its angularly adjusted position, a vertical semi-cylindrical reflector hood secured at its lower end to the marginal edge of the plate, and means for securing the upper end of the hood to the upper end of the lantern, whereby the direction of light-ray emission from the mounted position of the assemblage is selectively controllable by the rotative adjustment of the lantern supporting plate, said base unit including a plurality of arms radiating from the unit hub with one of the arms of greater length than the remaining arms, the extended arm having its free end zone upturned and perforated with the perforation axis extending horizontally, and a removable pivoting element extending axially through such end zone and forming a support for the clamping means to thereby locate the latter means in the vicinity of such arm and extending in general parallelism therewith, said clamping means being fashioned to permit a gripping relation

- 75

with the supporting unit for service, said clamping means being swingable about such horizontal pivot when the grip has been released and the assemblage bodily raised.

2. An assemblage as in claim 1 characterized in that the clamping means includes an arm having its outer end zone upturned and pivotally mounted on the pivoting element, said arm having a length to position its inner end adjacent the hub zone of the base unit, with said inner end having an integral contact member projecting downward from such inner end zone and adapted to engage a vertical face of the supporting unit, said arm having a downwardly extending ear located adjacent the outer end and spaced from said contact member a distance greater than the width dimension of the supporting unit, said ear having a thread zone extending horizontally in the direction of the contact member, and a threaded element mounted in said ear and formed to provide a second contact face for engaging the opposite vertical side of the supporting unit, said arm additionally carrying a planar member on its under side between the contact member and the ear and adapted to provide an extended face for contacting the upper face of the supporting unit, said planar member being dimensioned to also underlie the longer arm of the base unit, said planar member thereby controlling the projected height of the assemblage above the supporting unit in the service position of the assemblage with the integral contact member and the threaded element forming the

gripping faces for retaining the assemblage in gripped position and anchoring the base unit against rotation.

3. An assemblage as in claim 2 characterized in that the base unit further includes a ring-like formation carried by the free ends of the shorter arms, said formation having a raised zone with the zone lower face recessed to thereby place the formation as overlying the end zone of the longer arm and the adjacent clamping means when the assemblage is in service, whereby the clamping means will fixedly anchor the assemblage to the supporting unit during service with the base unit held fixedly in position and maintained against pivotal movement and with the lantern-supporting plate adjustable pivotally relative to the hub axis of the base unit.
